TAPE CYLINDER MOUNTING

Clarence M. Gentry and Fred G. Parrott,
Gastonia, N. C.

Application August 27, 1948, Serial No. 46,482

5 Claims. (Cl. 308—15)

1

This invention relates to improvements in spinning frames, twisting frames and the like, and more especially to an improved means for mounting the cylinders which extend longitudinally of the spinning frame and around which the tapes pass that drive the spindles.

Heretofore, in order to remove a cylinder from the spinning frame, twisting frame and the like, it has been necessary to remove the cylinder longitudinally from one end of the frame and then to remove the cylinders successively from the frame. It is often necessary to remove any one of the cylinders in a spinning frame, there generally being three or more, due to the bearings becoming worn or the cylinder being out of balance.

The primary object of this invention is to provide means whereby any one of the longitudinally extending cylinders may be removed from a spinning frame, twisting frame and the like, independently of the other cylinders and whereby the bearing block disposed between the proximate ends of any two of the cylinders may be removed or replaced as desired without the necessity of removing the associated cylinders from the machine.

It is another object of this invention to provide a head member for the proximate ends of the cylinder having a removable portion therein and to provide a bearing block in which the shaft disposed between the proximate ends of the cylinders is rotatably mounted and whereby the removable portion of the head member may be removed from the proximate ends of the cylinders and the shaft along with the bearing blocks may then be partially rotated to where the opposite ends of the shaft will pass out of the opposite sides of the cylinders and may thereby be removed from the bearing block without the necessity of removing the cylinders.

Some of the objects of the invention having been stated, other objects will appear as the description proceeds, when taken in connection with the accompanying drawings, in which

Figure 1 is a top plan view showing a plurality of the cylinders and showing portions of a spinning frame, twisting frame and the like, associated therewith;

Figure 2 is an enlarged elevation with parts in section and being taken along the line 2—2 in Figure 1;

Figure 3 is a sectional plan view taken along the line 3—3 in Figure 2;

Figure 4 is an enlarged top plan view showing the proximate ends of a pair of cylinders and the means for mounting the same;

Figure 5 is an elevation showing a portion of a Samson in cross-section;

Figure 6 is a vertical sectional view taken along the line 6—6 in Figure 5;

2

Figure 7 is a vertical sectional view taken along the line 7—7 in Figure 5;

Figure 8 is an isometric view showing one of the removable sections removed from the head member of the cylinder;

Figure 9 is a sectional plan view taken along the line 9—9 in Figure 5.

Referring more specifically to the drawings, the numerals 10 and 11 indicate the end frame members of a spinning frame, twisting frame and the like, and the numeral 12 indicates cross-bar portions of Samsons which are the intermediate frame members of a spinning frame or the like. In the present invention cross-bar portions of the Samsons 12 are provided with a suitable pin 13 located in the center thereof and projecting upwardly therefrom. This pin has slidably mounted thereon a bearing block broadly designated at 15. This bearing block 15 has outwardly extending base portions 16 having arcuate slots 17 therein which are adapted to be penetrated by screws 18 for securing the bearing block 15 to the Samson 12.

The bearing block 15 has a shank portion 20 which is square in cross-section and which may be engaged by an open ended wrench for rotating the bearing block 15 about the pin 13 when the screws 18 are loosened for removing the shaft, to be later described, which is associated with this bearing block 15.

The bearing block 15 has an enlarged upper portion 21 in which a suitable anti-friction bearing 22 is mounted and this anti-friction bearing 22 has a shaft 23 rotatably mounted therein. The opposite ends of the shaft 23 extend into head members broadly designated at 25 and being disposed at the outer ends of sheet metal tape cylinders 26. The head members 25 are preferably cast and each of the head members 25 comprises a bell-shaped portion 27 having its outer end ferruled as at 28 for securing the sheet metal cylinder 26 to the same. The bell-shaped portion 27 has integral therewith a boss portion 30 having a semi-circular cavity 31 therein which is adapted to engage the shaft 23 adjacent one of its ends.

Referring to Figures 5, 6 and 7 it may be observed that the sheet metal cylinder 26 is cut away along the lines 35 and 36 and the head member 25 is cut away along the lines 37 and 38, thus forming an opening for receiving an insertable member broadly designated at 40 (Figure 8).

The insertable member 40 comprises a curved sheet metal plate 41 which conforms to the curvature of the cylinder 26 and has its right-hand end 55 in Figure 5 recessed as at 42 and this recessed edge 42 is reinforced by a semi-elliptical strap member 43 which is curved to conform to the contour of the recess 42. This recessed portion 42 is adapted to cooperate with a semi-elliptical recessed portion 45 in the periphery of the cyl-

inder 26 and this recessed portion 45 is also reinforced with a semi-elliptical strap member 46 which conforms to the shape of the recess 45. These recesses 42 and 45 in the sheet metal plate 41 and the cylinder 26 form an opening 47 when the insertable member 40 is assembled with the cylinder 26, which provides access to screws to be later described and which secure the insertable member 40 to the boss 27 of the head member 25.

The insertable member 40 has a boss portion 50 and an outwardly extending plate portion 51 which is cast integral therewith and this outwardly extending plate portion 51 is bent upon itself to form a ferrule 52 which has the same radius as the ferrule 28. The left-hand end of the sheet metal plate 41 is confined in the ferrule 52 of the member 40. The right-hand end of the plate 41 extends to the points 55. The boss 50 of the member 40 has a semi-circular cavity 53 therein which conforms to and is adapted to engage the shaft 23 as the insertable member 40 is inserted in the opening defined by the lines 31 and 33 in the head member 25.

The boss portion 50 of the insertable member 40 is penetrated by screws 54 which are threadably imbedded in the boss portion 30 of the head member 25 to thus secure the member 40 to the head member 25. The opening 47, heretofore described, is provided for inserting a suitable socket wrench or the like therethrough for tightening the screws 54.

The description of parts refers to the bearings and shafts and the left-hand ends of the cylinders and like reference characters apply to the right-hand end of all of the cylinders with the prime notation added.

Now, when it is necessary to remove a shaft 23 from any one of the bearing blocks 15 or it is necessary to remove one or the other of the cylinders 26, it is merely necessary to insert a socket wrench or the like in the opening 47 and to loosen the screws 54 which secure the member 40 to the head member 25 and to thus remove the insertable member 40 from the cylinder 26. The same is true with the other of the cylinders 26 adjacent the same so the bearing block 15 may be rotated in the manner heretofore described to approximately the position shown in Figure 4. When the opposite ends of the shaft 23 have passed beyond the recessed portion 45 on the cylinders 26, it is obvious that the shaft may be withdrawn from the bearing block 15 and as a result, the proximate ends of the cylinders 26 would then be free to remove from the spinning frame, if so desired, or a new connecting shaft can be installed.

In the drawings and specification there has been set forth a preferred embodiment of the invention, and although specific terms are employed, they are used in a generic and descriptive sense only, and not for purposes of limitation, the scope of the invention being defined in the claims.

We claim:

1. In a textile machine such as a spinning frame and the like, having a plurality of longitudinally extending cylinders mounted therein and having Samsons and a shaft disposed between the proximate ends of the cylinders disposed therein, a bearing block for the shaft, a pivot pin projecting upwardly from the Samsons and on which the bearing block may be mounted for manual rotation in a horizontal plane, said cylinders having head members in the ends thereof and in which the remote ends of the shaft are fixedly secured, each of said head members and the

ends of the cylinders having coinciding openings therein in which an insertable member is disposed and said insertable members having means for clamping the same to the remote ends of the shaft, said shaft being rotatably mounted in the bearing block and whereby the insertable members may be removed from the head members in the proximate ends of two adjacent cylinders and the intervening bearing block may be partially rotated about its vertical axis to where the ends of the shaft will be moved through the openings in the cylinders, thereby permitting the shaft to be withdrawn longitudinally from the bearing block.

2. In a sheet metal cylinder for spinning frames and the like, a head member mounted in each end of the cylinder, each of said head members comprising a bell shaped member having a boss integral therewith, said boss having a semi-circular cavity therein and one end of a shaft being adapted to be inserted in the cavity, the end of the bell-shaped member being bent around the end of the sheet metal cylinder to form a ferrule for securing the sheet metal cylinder to the head member, said bell-shaped member having an opening therein, a removable member conforming to the shape of the bell-shaped member and having a boss thereon, said removable member being adapted to be inserted in the opening in the bell-shaped member, said removable member having a semi-circular cavity conforming to the diameter of the shaft and whereby the removable member may be mounted in the opening in the bell-shaped member and the boss of the removable member may be secured to the boss of the bell-shaped member for clamping the end of the shaft therebetween, the end of the cylinder having an opening therein and the removable member having an arcuate member secured thereto having the same radius as the cylinder for closing the opening in the cylinder.

3. Means for rotatably mounting and securing together the proximate ends of closely spaced cylinders in a spinning frame and the like, comprising a bell-shaped member mounted in the proximate ends of two adjacent cylinders, each of said bell-shaped members having an opening in one side thereof extending to the end of the cylinder, an insertable member adapted to be inserted in the opening and a shaft extending from one of the bell-shaped members to the other of the bell-shaped members and each of the bell-shaped members having means for clamping the insertable member to the bell-shaped member for securing the shaft in the cylinders, a Samson disposed between the proximate ends of the cylinders, a bearing block mounted on the Samson and in which the shaft is rotatably mounted, said bearing block having arcuate slots therein which are adapted to be penetrated by screws for securing the bearing block to the Samson whereby the insertable members may be removed from the shaft and the cylinders, and the screws may be loosened and the block may be rotated about its axis and the screws following the arcuate slots in the bearing block and the shaft may swing through the openings in the cylinders and the shaft may be moved endwise from its bearing.

4. Means for mounting for rotation and connecting together the proximate ends of tape driving cylinders in spinning frames, twisting frames and the like, comprising a bearing member mounted on a portion of the frame and extending upwardly and being rotatable on a vertical axis, a shaft rotatably mounted in said bearing mem-

ber and extending from each side thereof, a pair of cylinders having their proximate ends disposed adjacent each side of the bearing member and into which the two ends of the shaft project, a member mounted in each end of the cylinders and closing the ends of the cylinders and extending backwardly away from the ends of the cylinders and having means therein for receiving the ends of the shaft and detachably securing the ends of the shaft to said members, a portion of said member and a coinciding portion of the periphery of the respective cylinder being cut away, an insertable member disposed in said cut away portion, means for securing the ends of the shaft in position to thereby confine the shaft, each of the cylinders having an opening radially disposed from the securing means and through which a suitable wrench can be inserted for removing the cap member on the securing means, whereby the insertable member can be removed and the bearing member loosened so the bearing member and the shaft carried thereby can be rotated to a point where the shaft carried thereby can be removed from the cylinders through one of the openings formed by removal of the insertable member.

5. In a spinning frame, twisting frame and the like having Samson members and bearing members mounted on said Samson members and projecting upwardly, means for mounting the bearing members so they can be rotated on a vertical axis, each of said bearing members having a shaft rotatably mounted therein, said frame having a plurality of tape driving cylinders therein, the proximate ends of two cylinders being disposed

in spaced relation to each side of a bearing, a head member mounted in each cylinder and projecting away from the end of the cylinder and having a shaft receiving portion formed integral therewith, the head member and a coinciding portion of the periphery of the cylinder being cut away, an insertable member disposed in said cut away portion, said insertable member having a boss portion thereon, bolts for releasably securing the boss portion to the shaft receiving portion and the cylinders having an opening in their periphery radially disposed with relation to the bolts securing the boss portion in position, so the bolts can be removed when the boss portion is removed from the shaft receiving portion and whereby the said boss portion and the insertable member may be removed whereby the bearing member may be rotated on its vertical axis to a point where the shaft carried by the bearing member may be removed endwise from the bearing and out through the openings in the periphery of the cylinders formed by the removal of said insertable member.
